HOLDER FOR LIPSTICKS AND THE LIKE
COSMETIC MATERIALAndrew August Klippert, Hollis, N. Y., assignor
to Colgate-Palmolive-Peet Company, Jersey
City, N. J., a corporation of Delaware

Application April 19, 1949, Serial No. 88,354

3 Claims. (Cl. 206—56)

1

This invention relates to a new type holder for lipsticks and like cosmetic material which are projected from and retracted into the holder lengthwise as desired.

The operation of conventional lipstick holders require the usually independent functioning of screw, spring and slide projection type mechanisms for the advancement and retraction of the lipstick. Such types are of relatively complex and costly manufacture, and often difficult to operate satisfactorily.

Broadly, the instant invention involves the provision of a cosmetic container having a minimum number of simply designed, easily formed and inexpensively assembled parts and entirely operable by fluid pressure. Actuated by a pressure differential, the lipstick or similar cosmetic material may be ejected axially from the holder to a regulated height by the user simultaneously with and in synchronous relation with the removal of an outer slideable cap.

The invention comprises generally in its more specific aspects a slideable outer cap or cover in frictional contact with a lipstick casing having a perforation in the base thereof, said perforation being capable of closure by the positioning and pressure of a finger of the user against the opening. Within and in frictional contact with the casing proper is an elevator unit comprising an inner container holding the lipstick, which unit is slideably mounted in the casing and designed to slideably project lipstick from one end thereof.

For a fuller understanding of the invention, reference is made to the following detailed description taken in conjunction with the accompanying drawing, in which:

Fig. 1 is a view in vertical elevation of a lipstick holder with the closure cap in place, partly in section illustrating the various parts and a lipstick positioned therein.

Fig. 2 is a sectional view taken on the line 2—2 of Fig. 1 looking in the direction of the arrows.

Fig. 3 is a detailed partly sectional elevation of the lipstick holder with the cap removed illustrating the arrangement and operation of the parts when the lipstick is partially projected from the top of the holder for use.

Fig. 4 is a view partly in section of an alternative arrangement of the base of the container.

In the drawing similar reference characters are used to designate corresponding parts of all the views.

Referring to the drawing and particularly

2

Figs. 1 and 3 thereof, numeral 10 represents the slideable hollow outer cover or cap preferably completely or partially made of transparent material and whose open end telescopically fits over the lipstick casing 11. The outer closure cap 10 is preferably cylindrical in shape although it may assume any desired form such as of polygonal (e. g. square or hexagonal) or elliptical design in a transverse cross-section. Its design is such as to provide for the creation of a partial vacuum in the enclosed air space during the course of its removal from the casing 11. A friction fit with the complementary engaging surfaces of casing 11 is therefore desirable when slideable cap 10 is positioned thereon.

The casing or body member 11 is expanded to form a base 14 preferably having an outwardly projecting flange-like head or rim. Suitably disposed or formed in the base 14 is an aperture 15 communicating with the interior of holder 11, which will allow the inrush of air and formation of an air cushion or layer 16 when the elevator unit, comprising the lipstick 12 positioned in the carrier 13, is raised simultaneously and in synchronous relation with the removal of cap 10.

Slideably positioned and adapted to move axially by means of fluid pressure within the casing 11 is such elevator unit consisting at least of a cup or similar container 13 and a lipstick 12 positioned therein. The outer diameter of container 13 is such as to be in contact with the adjacent inner surface of casing 11 only to the degree required for its axial movement by air pressure differentials, such as a frictional fit.

The entire lipstick unit is operable by fluid pressure only and as illustrated in Fig. 3 is dependent upon the provision of pressure differentials. As the outer cap is removed, a partial vacuum is created in the enclosed air space in the cap which causes the elevation of the lipstick 12 and inner container 13 simultaneously with and in synchronous relationship with the cap removal. The movement of the cap 10 and the corresponding movement of the lipstick carrier 13 upwardly will thus ultimately project the body of the lipstick or other suitable cosmetic material beyond the outer end of holder 11. Concurrently, air enters the hole 15 in the base 14 of holder 11 and forms the air pocket cushion 16 inside the holder 11 and below the inner container 13. The lipstick 12 and inner container 13 are then fixed in the elevated position by placing a finger over the hole 15 thereby sealing the aperture. When the lipstick is applied to the user, the elevated inner container 13 holding the

lipstick proper is cushioned upon the resultant air pocket or cushion 16.

After usage, the finger may be removed from the hole 15 in the base 14 and the outer cap 10 is replaced upon holder 11, which operation depresses the lipstick 12 and inner container or carrier 13 due to the partial pressure inside the downwardly moving outer cap 10. At the same time with the return of the inner container 13 to a resting position upon the interior of holder 11, the air represented by the air cushion 16 is ejected through the hole 15 in the base 14.

The simple design, arrangement and functioning of the various parts readily and advantageously render possible certain optional operating modifications. Apart from the lipstick proper, the materials may be of metal or plastic construction, or any working combination of such materials. The outer cap, either partially or completely, is made preferably of a clear transparent plastic, such as for example, Lucite. In such case, the user can observe and regulate the degree of extension of the lipstick beyond the confines of the casing 11. When the lipstick has been advanced to the position desired by the user as determined by observation during the course of removal of the at least partially transparent outer cap, the lipstick may be fixed in such desired elevated position by the closure of the aperture in the base of the casing.

Similarly, the casing 11 may be constructed of metal, or plastic material, transparent or otherwise as desired. The use of resilient or springy plastic or metal, as for example brass, provides for an alternative means of fixing the lipstick and inner container in its elevated position during application of the lipstick. After the lipstick and inner container are elevated to the desired height for usage, the sides of the casing 11, constructed of a resilient or springy material, may be slightly distorted by applied finger pressure, thereby providing an alternative to the use of finger pressure on the air aperture.

This air aperture 15 may be located at any working point on the base 14 of the casing. It may be situated on the inner portion of the flange, or preferably on the periphery of the flange as shown in Figs. 1 and 3. An alternative modification is the insertion of the aperture 15 on any portion of the outer base as illustrated in Fig. 4. The positioning of the air opening is determined by an integration of the various factors of convenience of use, ease of manufacture, attractiveness, etc. Its position in the base should preferably be identified by an appropriate design, as for example by the use of a bead or a finger depression.

As previously disclosed, the contacts between the outer cap 10 and the outer surfaces of casing 11, and between the inner surfaces of casing 11 and the adjacent sides of the elevator or inner container 13 are such as to have a frictional relation and create the necessary pressure differentials during operation. If desired a lubricant may be used appropriately on one or both of these fits. The sides of the outer cap 10, casing 11 and elevator 13 may be parallel or substantially so preferably. However, if desired these sides may be permitted to taper provided the necessary fits between the complementary engaging surfaces are maintained. It is not necessary that the frictional effect be maintained along the entire adjacent surfaces, particularly with reference to the fit between the outer cap and the casing. It is sufficient if a portion of each of the adjacent sur-

faces is continuously engaged so as to always maintain a frictional factor. This construction may be incurred for example where the walls of the outer cap taper outwardly toward its closed end and the walls of the casing are parallel, whereby a frictional fit may be obtained between the lower open end portion of the outer cap and the corresponding engaging surfaces of the casing while the outer cap is positioned on the casing and during its removal therefrom.

In addition, the circumference or periphery of the casing 11 at or near its open end may be turned in to act as a stop, so that the elevator or inner container 13 cannot be removed during the elevating operation.

Thus by means of the arrangement and functioning of the various parts on a fluid pressure principle, no necessity exists for use of operating means of complex and relatively costly manufacture involving the conventional screw, spring and slide projection type mechanisms. The very simplicity of design of the minimum number of parts of my container, their easy formation and assembly consequently render capable facile and inexpensive manufacture.

The physical operations of the user are simplified since the outer cap may be removed and the lipstick ejected, or the parts restored afterwards to their normal position, simultaneously without the necessity of maintaining a particular relationship of certain parts manually by the user. For example, with certain projection type lipstick containers, the user must replace the cap in a predetermined manner in order to cause engagement of a particular notch with a projection. With other containers, after the outer cap removal screws, springs, levers, slides, etc. must be operated in a separate and usually independent step in order to elevate the lipstick for use. The present device obviates the need for such distinct procedures, and of course the possible difficulties and annoyances inherent in the functioning of such structures.

The invention may be carried out in other specific ways than those herein set forth without departing from the spirit and essential characteristics of the invention, and the present embodiments are to be considered in all respects as illustrative rather than limitative, and all coming within the meaning and equivalency range of the appended claims are intended to be embraced therein.

I claim:

1. A lipstick container comprising a slideable transparent outer cover positioned upon a lipstick casing, said lipstick casing having a base, imperforate side walls and a small aperture in the lower portion of said casing for admitting air to said casing, an inner lipstick containing member slideable axially within said casing and having a fluid tight frictional contact only therewith, and means for creating a partial vacuum above said inner member upon removal of said slideable outer cover to cause said inner lipstick-containing member to move axially.

2. A lipstick container comprising a closure cap in telescopic, slideable engagement with a casing, said casing having a base, imperforate side walls and being expanded at its base to form an outer rim and having an aperture on the periphery of such rim for admitting air into said casing; a lipstick carrier slideable axially within said casing and having a fluid tight frictional contact only therewith, and means for creating a partial vacuum above the inner lip-

stick carrier upon removal of said closure cap to cause said inner lipstick carrier to move axially into position for application of the lipstick.

3. A lipstick case comprising an outer cover in telescopic slidable relation with a casing, said casing having a base, imperforate side walls and a small opening in its lower portion for admitting air into its interior; an inner carrier for a lipstick slidable axially within said casing and having a fluid tight frictional contact only 10 therewith, and means for creating a partial vacuum above said inner carrier upon removal of said outer cover to cause said carrier to move axially.
